CLAIM

I claim the ornamental design for a food container, as shown and described.

DESCRIPTION

FIG. 1 is a perspective side view of a food container according to my new design;

FIG. 2 is an exploded perspective top and side view thereof;

FIG. 3 an exploded side elevation view thereof;

FIG. 4 is a side-by-side bottom plan view of the base and lid thereof; and,

FIG. 5 is a side-by-side top plan view of the base and lid thereof.
